CONTAINER CLOSURE

Albin H. Warth, Baltimore, Md., assignor to
 Crown Cork & Seal Company, Inc., Baltimore,
 Md., a corporation of New York

Application January 9, 1934, Serial No. 705,938

2 Claims. (Cl. 215—38)

The present invention relates to closures for containers and has as its object to provide such a closure having a sealing coating of improved characteristics.

5 Coating strata on the exposed undersurfaces of closures have long been used in the art, but heretofore they have had to be carefully selected with reference to the characteristics of the particular container contents. Coatings satisfactory for 10 use on closures for containers filled with one product are frequently unsatisfactory for association with other contained products, and the greatest care must be observed to insure the use of a suitable coating. For example, coatings satisfactory for use on closures for containers filled with an acid product may be entirely unsatisfactory for use with an alkaline product. An oil varnish coating, it may be stated, is not suitable for use with an alkaline product since 15 the effect of the alkali is to saponify the oil and thus destroy the coating.

Apart from these considerations, due regard must be had to the physical characteristics of the coating. It must be stable, odorless, tasteless, and readily handled. It should also have the attribute of mobility, that is, under application pressures, whether moderate or extreme, it should be able to accommodate itself to the minute irregularities present in the container 20 finish against which it seats in use. In other words, the coating should have some capability of flow so that it will conform somewhat to the opposed seating surface under ordinary application pressures. Oil varnishes possess this last attribute to a high degree, but as above intimated, oil varnishes have other serious disabilities.

In short, heretofore no universal coating material has been found, and by this I mean there has been found no coating material having the 25 desired physical qualities and yet of such composition as to be entirely unaffected as the result of contact with any of substantially the entire range of products ordinarily put up in bottles, jars and the like.

40 I have discovered that lacquers having a vinyl resin base completely fill the requirements above discussed. The vinyl resin base ordinarily vinyl acetate resin or a mixture of vinyl acetate and vinyl chloride resins, is transparent, odorless, tasteless and in a suitable solvent is readily applied to a clean surface to form a thin impervious adherent coating. In spite of the fact that the coating is tough and firm, it has the sealing characteristics of the best of oil varnishes. It is 45 stable, chemically inert, and is resistant to acids,

in any ordinary strength, to alkalis and to salts. It is ideal for use in the case of pharmaceutical preparations, foods, and beverages, and may be truly said to be of universal application.

The vinyl resin lacquer is applied to the exposed inner surface of removable closures of all types, such as screw closures, lug closures, friction closures, and closures of the crown type. While the coating may be applied directly to the closure shell or blank in some instances, I ordinarily prefer to apply the coating to a facing layer and to interpose a cushion liner between the facing material and the closure shell. The coating may be very advantageously used for foils such as zinc, tin, lead, and compositions and most particularly aluminum foil. Aluminum foil is obtainable in very light weights adequate for ordinary purposes. By reason of its light weight the aluminum foil, in the practice of the invention, is preferably mounted on a light weight 20 paper not only for the purpose of facilitating handling but also for the reason that as compared to tin foil, for example, it lacks conformability, unmounted, by reason of its relative stiffness. The foil is united with the paper by means of a 25 thermoplastic adhesive and this adhesive may be a suitable vinyl resin solution if desired, the adhesive stratum then serving as an auxiliary to the exposed vinyl resin coating stratum in enhancing sealing efficiency. For many types of 30 closures an even heavier cushion insert may be desirable. The mounted aluminum foil in this case may be affixed to a base of cardboard or the like. In some cases the aluminum foil may be applied directly to a cushion liner, such as cork. 35

I prefer to use the vinyl resin coating as an adjunct to a foil facing since foil has a smooth fine textured surface to which the lacquer may be most effectively applied, and I prefer aluminum foil on account of its cheapness due to the light 40 weight which may be satisfactorily used. Since aluminum foil is easily affected through contact with many substances and since through such contact it may adversely affect the substances, it must ordinarily be provided with a protective 45 coating of some nature. In view of the universal effectiveness of a vinyl resin coating the combination of the aluminum foil and the vinyl resin coating is extremely advantageous from all points of view. As above mentioned, however, the 50 lacquer may be applied directly to the closure material as to the exposed inner surface of a cap of metal or other material.

In short, the invention is not limited to use with closures of any particular design, make-up, or 55

The exposed lower surface of the metal shell or body has a coating 39 of vinyl resin applied directly thereto, and a compressible annular gasket 40 is interposed between the cap and the bottle.

- 5 5 The cap may be stamped from a pre-coated metal sheet and in this case, the entire inner surface of the shell will be protectively coated, as shown. On the other hand, the vinyl resin lacquer may be applied, as by spraying, to the formed shell and 10 10 the coating may be localized on the flat inner surface, if desired. When the lacquer is applied in this way, the gasket may be applied prior to the setting of the lacquer so as to be adhesively retained in place thereby.

- 15 15 15 In Figure 12 I have shown a liner material which contemplates a layer of foil 41 directly bonded to a cushion base 42 such as cardboard by means of a thermoplastic adhesive 43, such as vinyl resin, the exposed face of the foil carrying a coating layer 44 of vinyl resin. Discs of this material may be used in the manner indicated in Figure 5.

Figure 13 again shows a closure of the disc type. In this figure, however, the ductile body member 45 has applied thereto a facing 46 of the material shown in Figures 1 and 3. It will be evident that the thickness of the materials and of the adhesive and coating strata are considerably exaggerated in this view as well as in other views 30 30 of the drawings. Actually the material of Figures 1 and 3, for instance, is of slight thickness, as will be understood.

In Figure 14 I have shown a crown cap 47 having a cork liner 48 to which is directly applied a spot facing 49 of aluminum foil by means of a thermoplastic adhesive 50, the exposed face of the foil having a coating layer 51 of vinyl resin. Ordinarily, I prefer to use a paper mounted aluminum foil even when a thick cushion liner 40 40 is used since the paper enhances the sealing action of the foil. However, the unmounted foil may be used, particularly in the case of closures such as crown caps which are applied with a high application pressure.

In Figure 15 I have shown a portion of a metal screw cap 52 and a portion 53 of a bottle neck with which the cap is associated. The cap includes a facing layer 54 of the material shown in Figures 2 and 4. Figure 15 shows how the 5 5 layers 21 and 24, being assumed to be paper and cardboard respectively, are compressed between the shell and the lip of the bottle. It will also be noted that the vinyl resin coating 23 has flowed slightly at the edges of the neck under the pressure, materially enhancing the sealing effect. The vinyl resin, as above mentioned, behaves substantially as a long oil varnish under sealing pressures.

If desired, the vinyl resin lacquer may be colored, the coloring agents being chosen which are acid and alkali resistant, as Hansen yellow for a yellow lacquer.

It will be understood that the present disclosure is merely illustrative and not restrictive of 20 20 the invention as defined in the following claims.

I claim:

1. A container closure including a sealing cushion comprising a base of relatively thick and compressible substance, a facing of foil on said base 25 25 and affixed thereto by means of a stratum of thermoplastic adhesive, and a protective sealing film of vinyl resin lacquer on the exposed surface of said facing, said film being of such thinness that the foil does not lose its identity as 30 30 a sealing means.

2. A liner for container closures comprising a facing of relatively thin metal foil, not exceeding substantially .0010" in thickness, having 35 35 on its exposed surface a film of vinyl resin lacquer, a layer of paper beneath said metal foil united to the metal foil by a film of thermoplastic adhesive, and a base layer of relatively thick cushion material to which said paper layer is adhesively united, said lacquer film being of such 40 40 thinness that the foil does not lose its identity as a sealing means.

ALBIN H. WARTH.
